UNITED STATES PATENT OFFICE.

OTTO W. SCHAUM, OF PHILADELPHIA, PENNSYLVANIA, ASSIGNOR TO FLETCHER WORKS, INCORPORATED, A CORPORATION OF PENNSYLVANIA.

LOOM.

1,296,702.

Specification of Letters Patent. Patented Mar. 11, 1919.

Application filed April 13, 1916. Serial No. 90,803.

To all whom it may concern:

Be it known that I, OTTO W. SCHAUM, a citizen of the United States, and a resident of Philadelphia, county of Philadelphia, State of Pennsylvania, have invented new and useful Improvements in Looms, of which the following is a specification.

The invention relates to looms and particularly to narrow ware looms employing two or more banks of shuttles. In looms of this type it becomes necessary to raise and lower the banks of shuttles so that as desired any one of the banks of shuttles will be in operative position. This raising and lowering of the banks of shuttles is accomplished through the medium of a change-motion mechanism that is directly controlled by an indicator mechanism. A loom of the type referred to having a change-motion mechanism and an indicator mechanism for controlling the operation of the change motion mechanism is shown and described in Patents Nos. 786,237 dated March 28, 1905 and 803,511 dated October 31, 1905, which were granted to me respectively on those dates.

According to the present invention the indicator mechanism is constructed so that the members of the change-motion mechanism which are movable, will be positively moved from one extreme position to the other and back again. The change-motion mechanism is also constructed so that these movable members will be positively held in each extreme position by a cam which is constructed to effect the positive movement above referred to.

The invention relates to the features above referred to and also to other features which will be hereinafter pointed out in the several claims constituting a part of this specification.

As illustrating a specific embodiment of the invention reference is made to the drawing forming a part of this specification, and in which drawing—

Figure 1 is a side elevation showing the change-motion mechanism and the indicator mechanism for effecting a positive movement of the change gear of the change-motion mechanism from one extreme position to the other and back again.

Fig. 2 is a vertical view partially in section. This is a view looking at the change-motion mechanism and the indicator mechanism from the rear and a part of this figure

is a view taken as on the plane indicated by the line 2—2 of Fig. 1.

In said drawing the change-motion mechanism is designated by 1 and the indicator mechanism by 2. Said change-motion mechanism has a central crank-gear 3 which, as will hereinafter appear, may be properly referred to as the change-gear. Around this crank-gear there is arranged a semi-circular series of meshing gears 4, 5, 6 and 7. The crank-gear 3 is arranged so that it can be moved or swung laterally into engagement with one or the other of the end-gears 4 or 7 of the semi-circular series, as desired. These end-gears as well as the crank-gear 3 are properly mutilated in their engaging parts, as is usual in this type of construction so as to insure the proper meshing for the required semi-rotation of said crank-gear in opposite directions by the respective end-gears. The end-gear 4 may be considered as the prime mover and it continuously rotates. This gear, through the medium of gears 5 and 6 serves to continuously rotate the end-gear 7. As above indicated the crank-gear 3 may be and in fact is hereinafter frequently referred to as a change-gear of the change-motion mechanism since its function is to move in engagement with one of the end-gears to lower the crank pin 8 on the gear and to move in engagement with the other end-gear to raise said crank pin. This pin carries a link 9 through the medium of which motion is imparted from the change-motion mechanism to the bank of shuttles. The chain of gears which is arranged in a semi-circle about the change-gear or crank-gear 3 operates a second crank-gear 10 which may hereinafter be referred to as the indicator crank-gear because its function is to actuate the link through which motion is imparted to the indicator mechanism.

The function and mode of operation of the gears just described are the same as that of the corresponding gears which are fully shown and described in the patents above referred to. The gears 4, 5, 6, 7 and 10 are all carried on shafts or pins that pass through or are carried by a frame member 11. On this frame member 11 a lever construction 12 is pivotally mounted at 13. At the lower end of this lever construction there is carried the change-gear 3 heretofore referred to. This lever construction also preferably carries a stop 14 which is

engaged by the parts 15 and 16 so as to limit the movement of this change-gear and also so as to absorb any vertical thrust which may be imparted to the stop while the 5 change-gear through the medium of the link 9 is supporting the bank of shuttles in one of its extreme positions. This lever construction 12 may in one sense be considered to constitute a part of the change-motion 10 mechanism, since one of its functions is to support the change-gear in position. This lever construction may also be considered to constitute a part of the indicator mechanism since it is under the positive control 15 of a box-cam construction 17 which is a part of the indicator mechanism, thus serving to properly position as desired the change-gear 3 in respect to its driving-gears. This box-cam construction comprises parts 18, 19 and 20 that may in effect be considered three cam elements of a single cam construction. The cam members 18 and 20 are each constructed alike or substantially alike and merely serve to divide the work of operating 25 the lever construction. The lever construction comprises lever elements which may be considered as constituting a single lever. The box-cam construction, to wit, the cam member 19 thereof, has a double-sided race-way 17 one side portion of which engages one side of a pin or roller 12' on the lever 12 to positively force the lever in one direction, the other side portion of which engages the other side of the pin or roller 12' to 30 positively force the lever 12 in the opposite direction. As above indicated a cam which will satisfy this condition is a box-cam. The lever 12 and the parts associated therewith may be referred to as an intermittently 35 movable element which is actuated by a box-cam that positively moves the change-gear from one extreme position to the other and back again. The box-cam when at rest also positively holds said lever 12 and the 40 change-gear carried thereby in each of their extreme positions. In order that the cam may be locked when at rest a link construction 21 is positively mounted upon a pin—or pins—22 that passes through a slotted 45 portion 23 in the main frame member 11. At the free end of this link construction 21 there is provided a roller—or rollers—24 that enters a dwell 25 in the box-cam. This roller and the members whereby it is held 50 in place may be referred to as mechanism for holding or locking the cam in each of its several positions of rest and therefore may be properly called a holding mechanism or locking mechanism. The pin 22 which carries the link 21 is adjustable along 55 the slot 23 in order to facilitate a change of the position of these rollers 24 which serve as locking rollers for the cam. A spring 21' is secured to the pin at 21'' and 60 presses against the link 21 in a manner to

force the roller at the free end of the link against the cam. A ratchet 26 is secured to each of the cam elements 18 and 20 and each of these ratchets is engaged by a pawl 27 that is mounted upon an oscillating carrier 28. This pawl is normally pressed in engagement with the ratchet through the medium of a spring 29 one end of which spring engages the pawl 27 and the other end of which engages a portion of the carrier 28. The ratchet and the carrier therefore are oscillated through the medium of a connecting link 31 that is pivotally connected at its upper end 32 to the pawl carrier. The lower end of this link is slotted at 33 and receives a crank pin 34 which is on the gear 10 heretofore referred to as the indicator crank-gear. This gear in effect constitutes a continuously moving element that is a part of the indicator mechanism. At 35 times it is necessary to render the indicator mechanism functionally inoperative in order that the change-motion mechanism will remain as it is. This is accomplished through the medium of a guard or pawl engaging portion 30 that is on a member 35 which can be positioned so that the guard will raise the pawl and so that the latter cannot engage the teeth of the ratchet. This member 35 is maintained in its lower position by means of a tension spring 37, except at such times as when it is raised through the medium of a cord or other connecting element 38 leading from and that is under the control of the jacquard mechanism with 40 which looms of this class are provided. This member 35 since it is under the control of the jacquard will be hereinafter frequently referred to as a pattern-controlled member. It will therefore be seen that when desired, according to the design of the jacquard this pattern-controlled member will render the indicator mechanism functionally inoperative thereby permitting the change-motion mechanism to remain as it is. If it is desired, at any time, to impart to the box-cam a partial revolution in order to change the position of the change-gear, this can be accomplished by grasping the handle 39 which is on the pawl carrier and moving 45 the latter forward, if it becomes necessary. This movement is permitted to take place due to the slot 33 in the connecting link 31 which allows the link 31 to move longitudinally and upwardly along the crank 50 pin 34.

It will be observed that in the construction shown there are a plurality of ratchets, a pawl for each ratchet, carriers for the pawls and connecting links for actuating 55 the pawl carriers, but it will be manifest that these may constitute a part of a single mechanism of which the several ratchets, the several pawls, the several carriers and the several links may be considered to con- 60

stitute or make up, respectively, a single ratchet, a single pawl, a single carrier and a single link, they merely being separated into different parts whereby the loads upon 5 the several parts can be applied in an advantageous manner.

The improvements herein set forth are not limited to the precise construction and arrangement shown and described for they 10 may be embodied in various forms and modifications without departing from the spirit and scope of the invention.

What I claim is:

1. A loom having in combination with the 15 change-motion mechanism an indicator mechanism comprising an indicator cam having a ratchet secured thereto, a continuously moving pawl for operating said ratchet, which pawl is provided with spring 20 means for pressing said pawl against said ratchet, a jacquard-controlled indicating lever for determining the operative relation between the ratchet and pawl, the change-gear of the change-motion mechanism being 25 carried by a lever which is positively actuated by said cam, which cam has a double sided raceway portion constructed so as to positively move said pawl and change-gear from one extreme position to its other 30 extreme position and back again and also constructed so as to hold said lever in each of its extreme positions when the cam is at rest.

2. A loom having in combination a 35 change-motion mechanism for positioning a shuttle carrier and an indicator mechanism, said indicator mechanism comprising a cam which is actuated as desired, there being an intermittently-movable lever which carries at the lower end thereof a change-gear of 40 the change-motion mechanism and which lever is positively engaged by the cam whereby said lever will be positively reciprocated by said cam.

3. A loom having in combination a 45 change-motion mechanism for positioning a shuttle carrier and an indicator mechanism for said change-motion mechanism, said indicator mechanism comprising a box-cam which is actuated as desired, there being an 50 intermittently-movable lever which carries at the lower end thereof a change-gear of the change-motion mechanism and which lever is positively engaged by the box-cam whereby said lever will be positively reciprocated in opposite directions by said box-cam.

4. A loom having a change-motion mechanism and an indicator mechanism, said indicator mechanism comprising an intermittently-movable member, continuously operating means for moving said member, and a pattern-controlled device for rendering the continuously-operating means functionally operative or inoperative as desired, the continuously-operating means for moving said

element comprising a continuously rotating crank, a link which has an elongated slot in which the crank-pin of said crank enters, a carrier and pawl mounted thereupon, to which carrier the link is also connected, and 70 a handle whereby the carrier and pawl thereupon together with the link can be moved a relative distance so that the slotted portion of the link will move relative to the crank-pin whereby the cam can be moved by hand 75 a limited distance independent of the mechanism which normally actuates the link.

5. A loom having in combination a 80 change-motion mechanism for raising and lowering banks of shuttles, and an indicator mechanism having a cam which directly engages a roller on a lever carrying the change-gear of the change-motion mechanism, which lever has thereupon a stop that is engaged by the change-gear when the 85 latter is supporting the bank of shuttles in either of its extreme positions.

6. A loom having in combination an indicator mechanism and a change-motion mechanism in which change-motion mechanism there is a change-gear carried by and at the lower end of a lever that is pivotally mounted on the frame of the loom and which lever is provided with a stop that is engaged by the change-gear, said indicator mechanism having a cam which engages and operates said lever. 90

7. A loom having in combination a 95 change-motion mechanism for positioning a shuttle carrier and an indicator mechanism, 100 said indicator mechanism comprising a cam which is actuated as desired, there being an intermittently-movable lever which carries upon an arm thereof a change-gear of the change-motion mechanism and which lever 105 is positively engaged by the cam whereby said lever will be positively reciprocated by said cam.

8. A loom having in combination a 110 change-motion mechanism for positioning a shuttle carrier and an indicator mechanism for said change-motion mechanism, said indicator mechanism comprising a box-cam which is actuated as desired, there being an intermittently-movable lever which carries 115 upon an arm thereof a change-gear of the change-motion mechanism and which lever is positively engaged by the box-cam whereby said lever will be positively reciprocated in opposite directions by said box-cam. 120

9. A loom having in combination a 125 change-motion mechanism for positioning a shuttle carrier and an indicator mechanism, said indicator mechanism comprising a box cam, a pattern-controlled means for actuating said box-cam at periods determined by a pattern and an intermittently-movable member upon which there is supported a change-gear of the change-motion mechanism, said intermittently-movable member 130

being positively actuated by the box cam in such a manner that said member will be positively reciprocated by said box cam, said loom also comprising a locking mechanism 5 for engaging and holding said box cam when said box cam is at rest.

10. A loom comprising a change-motion mechanism having a change-gear for elevating and lowering the banks of shuttles of the loom, a pivotally mounted bell-crank lever having a depending arm upon the lower end of which said change-gear is carried, a stop on said lower end for limiting the movement

of the change-gear relative to said arm, and an indicating mechanism comprising a pattern-controlled box-cam that engages a roller on the other arm of said lever so as to positively move said lever in opposite directions.

This specification signed and witnessed 20 this 6th day of April A. D., 1916.

OTTO W. SCHAUER.
